LOCK NUT

Robert C. Sherwood, West Hollywood, and
Bertrand Deleray Mouron, San Marino,
Calif.

Application October 1, 1948, Serial No. 52,204

2 Claims. (Cl. 151—19)

1

This invention relates to lock nuts.

Some difficulty has heretofore been encountered in the prior art in making a low cost lock nut having a drawn shell capable of withstanding a substantial locking or radial load.

This and other difficulties are overcome by the instant invention by predetermining the locking limits of the compressible core while relieving the shell and bolt of excessive torsional strain. Axial load tension is nevertheless maintained at a high value. It has simultaneously been possible to accommodate lock nuts to bolts of extremes of pitch diameter within any given size, whether these be of high or low manufacturer's tolerance.

It is among the objects of this invention to provide a lock nut suitable for commercial bolts of extreme pitch diameter within any given size.

It is another object of the invention to provide a new and improved lock nut having an economical stamped shell and provision for added strength incorporated therein where needed but independently of the shell.

It is another object of this invention to provide in a lock nut of the desired character described, means for pre-establishing the limits of constricting and/or relative axial movement of the bolt-engaging core regardless of added wrench torque.

Another object of this invention is to provide an improved keying means to prevent rotation but permit longitudinal movement of the operative parts.

Yet another object of the invention is to provide a core-constricting means independent of the shell and whose resistance to radial expanding forces is independent of the shell.

It is moreover among the objects of this invention to provide improvements over prior art lock nuts intended for a generally similar purpose.

With these and other objects in view, the invention consists in the construction, arrangement and combination of the various parts of the device whereby the objects contemplated are attained, as hereinafter set forth, pointed out in the appended claims, and illustrated in the accompanying drawings.

In the drawings:

Figure 1 is a side elevational view of a lock nut as used.

Figure 2 is a plan view.

Figure 3 is a vertical sectional view of a lock nut embodying this invention as used prior to the application of core-constricting tension.

Figure 4 is a view similar to Figure 3 showing

the parts after the completion of application of core-constricting tension.

Figure 5 is a perspective view of a core removed from the shell.

Referring more particularly to the drawings, a lock nut chosen as illustrating, without limiting, the invention is generally designated by the numeral 10 and may be used with a bolt 11. Working surfaces or bolted materials as generally designated at 12 comprise, for example, sheets 13 and 14 apertured as at 15 for the insertion of the bolt shank 17.

A sheet metal shell 10 is preferably polygonal, i. e., hexagonal, in cross-section or as illustrated most clearly in Figure 2 from the top edge 21 to the bottom edge 22 thereof. At the top edge any suitable means as peening, upsetting, indenting, spinning or the like may be employed for confining a constrictable core 23 within the shell. As illustrated, this is done by any number of inwardly turned ears 24 preferably corresponding with the flat sides of the shell.

The bottom 22 of the shell may be rounded as at 25 and formed with an inturned annular shoulder 26 defining a bolt-receiving hole 27.

The core 23 (cf. Figure 5) may have a hexagonal upper end or half 28 and a lower tapered end or half 29 defining an annular abutment 30. The upper surface 31 of the core, as well as the lower end 32, may be flat, the former having optionally rounded edges 33 for clearing any upset portion of the ears 24 permitting the core freely to engage said ears.

A constricting ring 35 of a preferably hexagonal, cross-sectional configuration makes, like the core a slip fit within the interior 36 and bottom 37 of the shell. As illustrated, the ring 35 is hexagonal to conform with the interior configuration of the shell. Another, though less desirable, construction would give the ring 35 and the inner lower half of the shell a substantially cylindrical form.

An upper portion or half 39 of the ring is tapered, preferably to match the taper of the lower half 29 of the core while the lower end or half 40 of the ring may be cylindrical. The top 41 of the ring is preferably flat to match the abutment 30 in the core.

As illustrated, the core is split at 42 and a diametrically opposite slot 43 increases its flexibility. The stock between the bottom of the slot 43 and the thread 44 of the core should be of a sufficient thickness to permit ready compressibility of the right and left halves 45 and 46 of the core 55 without interfering with the ability of the core

to return, spring-like, to its normal expanded position (Figures 2, 3, and 5). Any other number of slots similar to slot 43 may be provided at spaced intervals around the core as desired. It is also within the spirit of this invention to eliminate all slots similar to 43 leaving only the slot 42.

Operation

In the use of the lock nut herein set forth, the shank 17 of a bolt is applied to the nut in the usual manner through the opening 27 in the shell and the coincident cylindrical bore in the ring 35. The thread 44 of the core is meshed loosely with the threads upon the bolt while the core is in the upper end of the shell, as illustrated most clearly in Figure 3.

When the head of the bolt firmly engages the lower work surfaces 14 and the shell bottoms firmly on the upper work surfaces 13, continuous turning of the nut will draw the core 23 downwardly, the tapered lower end 29 thereof being drawn down into and compressed within the tapered upper end 39 of the ring 35 until the shoulder 30 abuts the uppermost edge 41 of the ring.

Such abutment establishes the maximum limit of downward movement of the core 23 and, in addition, the core is thus restricted to its utmost, then occupying a substantially central position within the shell and firmly engaging the bolt to lock the nut thereon. The nut cannot be removed without overcoming the clamping action of the core which is generally relieved, depending upon the angles of taper of the core and ring, by the initial turns made to remove the nut from the bolt. To prevent the ring from "following" the core during this operation the ring may be press fit into the shell, or otherwise held therein.

Any preferred degree of taper of the lower portion 29 of the core or the conical portion 39 of the ring may be provided. By way of example, it has been found desirable in a three-eighths inch nut to provide a six-degree taper but this size, as well as larger sizes, has been found to operate properly with tapers of from three to nine degrees. A class 2-type bolt which has been tapered approximately sixteen degrees in sizes up to one inch functions properly within the usual extremes of manufacturing tolerance in pitch diameter variation.

The tapered surfaces at 29 and 39 are preferably identical although they may be made to vary from one another for line contact where excessive loads are not encountered.

Nuts of this character may be formed economically by stamping or drawing the shell during the manufacturing process and separately machining or otherwise forming the core and ring. The strength of the nut and of the ring is independent of the shell and the degree of taper need not be limited due to the strength of the shell, the slighter degrees of taper furnishing a more forcible and slower clamping action than the greater degrees of taper. In any event, the shell, relieved of radial stresses, merely serves as an envelope to hold the operating parts in a desired functional relationship. The conforming surfaces of the core and ring and the preferable slidable fit of the former and optional slidable or press fit of the latter within the shell minimize distortion of the shell through application of relatively high wrench torque, not otherwise possible in lightweight or drawn shells of this character.

In view of the permitted predetermination of the maximum extent of clinching action of the

core by adjusting the degree and extent of taper through the relative positions of the abutting surfaces 30 and 41, a maximum tension loading axially is achieved with a minimum load torsionally, and the liability to galling of the threads of the nut or bolt or the breakage of the bolt to excessive torsional strain, particularly where slight tapers are used, is virtually eliminated.

This invention features the provision of a drawn lightweight shell confining a core and ring independently made by any suitable process as by casting or machining. The invention also features a lock nut of great strength and adaptability producible at low unit cost.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

Having described our invention, what we claim as new and desire to secure by Letters Patent is:

1. In a free type collet-acting lock nut comprising an outer sheet metal type shell and an inner constrictable longitudinally split core: said shell being substantially cup-shaped and having hexagonal side walls, the bottom of the shell being formed with a central aperture defining an annular bottom shoulder therearound; said core having an axial threaded bore, hexagonal upper sides slidably nested within the hexagonal shell and reinforcing said shell against wrench-compressive forces, and a frusto-conical lower portion inset from the hexagonal sides defining an annular abutment between the upper and lower portions of the core: the improvement comprising a steel reinforcing ring having a length greater than that of said frusto-conical portion and a top annular shoulder for engagement in the extreme position of core constriction with said annular abutment, a tapered bore for constrictable reception of the frusto-conical portion of the core, and bottom edges nested within the bottom portion of the shell upon and against said annular bottom shoulder, said ring top shoulder receiving the axial thrust of the core and transmitting said thrust by means of said ring directly against said annular bottom shoulder, said bottom shoulder being pinched and held between said ring and a work surface when applied to a bolt under tension.

2. In a free type collet-acting lock nut comprising an outer sheet metal type shell and an inner constrictable longitudinally split core: said shell being substantially cup-shaped and having hexagonal side walls, the bottom of the shell being formed with a central aperture defining a bottom shoulder therearound; said core having an axial threaded bore, hexagonal upper sides slidably nested within the hexagonal shell and reinforcing said shell against wrench-compressive forces, and a frusto-conical lower portion inset from the hexagonal sides defining an abutment between the upper and lower portions of the core and a steel reinforcing ring having a length greater than that of said frusto-conical portion, and a top shoulder for engagement in the extreme position of core constriction with said abutment, a tapered bore for constrictable reception of the frusto-conical portion of the core, and bottom edges positioned within the bottom portion of the shell upon and against said bottom shoulder, said ring top shoulder receiving the axial thrust of the core and transmitting said thrust by means of said ring

directly against said bottom shoulder, said bottom shoulder being pinched and held between said ring and a work surface when applied to a bolt under tension.
